TELESCOPIC MAST

Walter C. Howard, Pioneer, Calif.

Filed Sept. 10, 1957, Ser. No. 683,072

2 Claims. (Cl. 189—26)

This invention relates to a method of and means for erecting a mast such as a mast to be used for supporting a television or radio antenna.

The object of the invention is to provide a means whereby an extensible or telescopic mast can be readily extended or raised and wherein the mast can be raised with a minimum of effort and wherein extremely high masts can be erected by using the principle of the present invention.

A still further object of the invention is to provide a means for erecting a telescopic mast wherein there is provided a control cable which is arranged in engagement with a pulley, and wherein the control cable is connected to a slidable member, the member having guy lines connected thereto so that by pulling on the control cable, tension on the guy lines or guy wires can be maintained at the proper amount whereby a person can more easily and quickly erect a mast, as for example when a mast is being erected to be used for supporting a television antenna.

A further object of the invention is to provide a telescopic mast which is extremely simple and inexpensive to manufacture.

Other objects and advantages will be apparent during the course of the following description.

In the accompanying drawings, forming a part of this application, and in which like numerals are used to designate like parts throughout the same.

Figure 1 is a longitudinal vertical sectional view of the telescopic mast of the present invention showing the parts in lowered position.

Figure 2 is an enlarged sectional view similar to Figure 1, but showing a first step position in raising the mast.

Figure 3 is an elevational view, showing the next position after Figure 2 in the raising of the mast.

Figure 4 is a sectional view showing the position of the parts after the mast has been raised all the way up and showing the guy wires anchored or fastened in place.

Figure 5 is an enlarged elevational view illustrating the slidable support member.

Figure 6 is a top plan view of the support member of Figure 5.

Figure 7 is an elevational view illustrating the bracket which supports the pulleys.

Figure 8 is a plan view of the bracket of Figure 7.

Figure 9 is a fragmentary sectional view illustrating certain constructional details of the present invention.

Figure 10 is a perspective view of the slidable support member.

Referring in detail to the drawings, the numerals 10, 11 and 12 indicate a plurality of telescoping sections which are of different diameters, and while the present invention has been illustrated for use with a mast having three sections 10, 11 and 12, it is to be understood that the principle of the present invention is applicable to masts having any desired number of sections. Extending upwardly from the upper section 12 and secured thereto is an upstanding rod or pole 13 which is adapted to pro-

2

vide a support for a member 14 which may be a television antenna.

Extending outwardly from the upper ends of the sections 10 and 11 of the mast are apertured ears which are indicated respectively by the numerals 15 and 15' and guy lines 16 and 16' are connected to the ears 15 and 15', the lower ends of the lines adapted to be connected to pegs or anchoring elements 17 which project upwardly from the ground 18.

Referring to Figures 7 and 8 of the drawings, there is illustrated a bracket which is indicated generally by the numeral 19, and the bracket 19 includes a pair of spaced parallel portions 20 which are connected by means of an end portion 21, and the portions 20 terminate in curved portions 22 which straddle the rod 13. Lips 26 extend from the curved portions 22, and the lips 26 have a suitable bolt and nut assembly 27 extending therebetween whereby the bracket 19 can be secured to the lower portion of the rod 13. A bolt 23 extends between the portions 20 of the bracket 19, and a pulley 24 is mounted on a bolt or pin 25 as shown in Figures 7 and 8 for example. The numeral 28 indicates a control cable which is trained over the pulley 24, and the control cable 28 may have a hand loop 29 on one end thereof.

There is further provided a slidable support member which is indicated generally by the numeral 30, Figures 5 and 6. The support member 30 may consist of a pair of similar pieces 31 which in their assembled position form a cylindrical member that slidably engages one of the sections such as the section 12. The pieces 31 are provided with lips 32 which are connected together by suitable bolt and nut assemblies 33, and extending outwardly from the upper end of the support member 30 is an apertured lug 34 which is adapted to be connected to an end of the control cable 28. Extending outwardly from the lower end of the support member 30 is a plurality of apertured ears or lugs 35, and these ears 35 are adapted to have guy lines such as the guy lines 16" connected thereto. The numeral 36 indicates a bolt which may be extended through openings 36" and 36'" in the sections 10 and 11 whereby these sections will not accidentally move downward. The bracket 19 is also provided with apertures or openings such as the openings 37 whereby guy lines 16' may be connected thereto.

From the foregoing, it is apparent that there has been provided a method of and means for erecting a telescopic mast, and wherein according to the present invention there is provided the sliding guy line ring or member 30 which is long enough to slide smoothly without binding, and wherein the length of the member 30 may be at least twice its diameter. This member may be made of lightweight material such as mast stock. On one end of the member 30 there are the plurality of ears 35 which can be formed by cutting into and bending out the lower portion of the member 30, and these ears 35 have holes therein whereby guy lines such as the guy lines 16" can be connected thereto. On the other or upper end of the support member 30, there is provided one or more ears or lugs 34 which are made in the same way. The pulley bracket 19 is clamped onto the rod or mast 13, and the control cable 28 may be a length of guy line. To put up a high mast, such as a television antenna, or other type of mast, the following procedure is followed. With the mast closed as for example as shown in Figure 1, the bottom can be secured in place and then the mast is plumbed and then the first guy lines 16 which extend from the upper end of the section 10 are secured in the usual manner as for example to the anchors or pegs 17. Then, with all of the guy lines, and with the support member 30 and other parts in their proper places, and with the member 30 on the section 12, the pulley bracket 19 can be clamped on the lower end of the rod 13 whereby the

pulley 24 will be positioned directly over the sliding member 30 with nothing therebetween to interfere.

Next, the user fastens one end of the control cable 28 to the lug 34 on the member 30 and to the other end of the cable 28 is allowed to hang down alongside the mast. Then, the user lifts up the two top sections 12 and 13 as for example from the position shown in Figure 1 to the position shown in Figure 2, and these sections are locked in position by means of a bolt such as the bolt 39 which is extended through the registering apertures 39' and 39". Tension is maintained on the control cable 28 at all times whereby the sliding member 30 can be pulled up, and after the parts have been moved to the position shown in Figure 2 the bolt 39 is extended through registering apertures or openings 39' and 39" in the sections 11 and 12, and then the guy wires or lines 16" are fastened to the ground as at 17 and the use of the guy wires helps insure that the antenna or member 14 will be held steady so that the tendency of the antenna to sway in the wind will be minimized. Tension is maintained on the cable 28 during the raising of the mast, and after the parts are moved to the position in Figure 2, the bolt 39 is extended through the registering apertures 39' and 39" so as to prevent the mast from collapsing or accidentally moving downward. With the parts in the position of Figure 2, the mast can be further extended upwardly by manual pressure so that the mast can be extended from the position shown in Figure 2 to the position shown in Figures 3 and 4 and when the parts are in the position of Figure 3 the bolt 36 is extended through the registering apertures 39' and 39", it being understood that during this action, tension is maintained on the line or cable 28, and tension is maintained on the control cable or line 28 by holding the control cable 28 against the mast with the hands, and the hands of the user can be moved hand over hand as the mast is being extended upwardly whereby the cable 28 will be held tight against the mast at all times. After the mast is fully extended or raised, all of the guys such as the guys 16" are anchored as at 17 in order to maintain the mast in its extended position, and with the bolts 36 and 39 in place in their registering apertures, and with the guy lines taut, manual pressure can be released and the mast will remain immobile in its extended position. The cycle above set forth is adapted to be repeated so that the various sections can be erected. This is continued until the mast is fully extended and then all of the guy lines are secured and the job is completed. On an extremely high mast, more than one rigging can be used and these may be fastened together or used singly. By using the principle of the present invention, a mast several hundred feet high may be erected.

The device of the present invention will permit one person to keep a telescopic mast safely guyed while it is being erected and the present invention will permit the use of taller masts. The present invention will also reduce high mast installation costs since the mast can be erected with a minimum of help. According to the method of the present invention, the mast can be erected quickly and safely because the mast is held steady at all times and it is not necessary to rely on the ability of the guy line attendants to release the cable smoothly and uniformly.

Thus, according to the present invention when the mast is being raised, the sliding member is placed in position at the starting position at the top of the particular section,

and then the control cable 28 is pulled snug and then the hands of the user are clamped tightly over the control cable against the section of the mast that is being lifted and the hands can be moved hand over hand as the mast goes up so that the cable is held tightly against the mast at all times. By having the support member made of split parts 31, this member can be taken apart and fastened together over the mast rather than being slipped over the ends of the mast. The bracket 19 is constructed so that there will be no chance of the control cable accidentally working loose or coming off of the pulley. As previously described, the support member 30 may be made in two halves or two pieces 31 for ease of installation or assembly.

I claim:

1. In a mast, a plurality of telescopic sections including a lower section, an upper section, and at least one intermediate section, a rod extending upwardly from the upper section and secured thereto, a body member connected to the upper end of said rod, a bracket secured to the lower portion of said rod and said bracket including a pair of side members each having a first portion, a pulley journaled between said first portions, a control cable trained over said pulley, said bracket further including curved portions surrounding said rod, and said curved portions terminating in spaced parallel lips, securing elements extending between said lips and connected thereto, a support member slidably connected to said intermediate section, an apertured lug extending from the upper end of said support member and connected to an end of said control cable, a plurality of apertured ears extending outwardly from the lower end of said support member, guy lines connected to said ears, and a plurality of guy lines extending from the upper ends of said sections and adapted to be anchored in a lower supporting area.

2. In a mast, a plurality of telescopic sections of different diameters including a lower section, an upper section, and at least one intermediate section, a rod extending upwardly from the upper section and secured thereto, a body member connected to the upper end of said rod, a bracket secured to the lower portion of said rod and said bracket including a pair of side members each having a first portion, a pulley journaled between said first portions, a control cable trained over said pulley, said control cable having a hand loop on one end thereof, said bracket further including curved portions surrounding said rod, and said curved portions terminating in spaced parallel lips, securing elements extending between said lips and connected thereto, a support member slidably connected to said intermediate section, an apertured lug extending from the upper end of said support member and connected to an end of said control cable, a plurality of apertured ears extending outwardly from the lower end of said support member, guy lines connected to said ears, and a plurality of guy lines extending from the upper ends of said sections and adapted to be anchored in a lower supporting area, said support member including a pair of similar pieces which are connected together.
